UNITED STATES PATENT OFFICE

2,076,559

GAS AND AIR MIXING DEVICE

William A. Hauer, Youngstown, Ohio

Application December 16, 1935, Serial No. 54,731

2 Claims. (Cl. 123—119)

This invention relates to gas and air mixing devices for internal combustion motors.

When a vehicle motor is suddenly accelerated, for example, starting from a stop, or passing another vehicle, the sudden acceleration of the motor reduces the vacuum pull in the intake manifold. The present invention provides apparatus for utilizing this decrease in the vacuum to shut off a predetermined amount of air so that a richer mixture may be supplied to the motor until the motor has picked up speed to restore vacuum in the intake manifold. Thus a stronger charge is supplied to the motor to increase the power of the motor and simultaneously economize in the use of fuel at all speeds above idling speed.

A further object of the invention is to provide a gas and air mixing device having a manually adjustable sleeve valve for controlling the air intake.

A further object is to provide a device of this character which will operate with the accelerator and throttle rods and the intake manifolds of all standard motors.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a longitudinal sectional view through a gas and air mixing device constructed in accordance with the invention.

Figure 2 is a plan view of the parts shown in Figure 1.

Figure 3 is a cross sectional view taken on the line 3—3 of Figure 1.

Figure 4 is a cross sectional view taken on the line 4—4 of Figure 1.

Figure 5 is a detail cross sectional view taken on the line 5—5 of Figure 1 with the valve closed.

Referring now to the drawing in which like characters of reference designate similar parts in the various views, 10 designates a cylinder which is open at one end to receive a cylindrical hollow piston 11. A pin 12 is secured in the open end of the piston and a rod 13 is threaded at one end, as shown at 14, and screwed into a threaded opening 15 formed in the pin. The rod is provided with a laterally directed free end 16 which is orificed, as shown at 17, to receive any suitable

connector for attaching the rod to the accelerator rod of the motor.

The cylinder 10 is closed at one end by a flanged cap 18 having a nipple 19. A T-coupling 20 has one leg threaded on to the nipple 19. The shank 21 of the coupling is adapted to be threaded into a suitable opening in the intake manifold 22 of the motor. Thus the cylinder 10 may be subjected to fluctuations in the suction or vacuum as it is termed, in the motor.

A valve housing 23 is disposed in the closed end of the cylinder and extends exteriorly of the cylinder. A plunger valve 24 is slidably fitted in the housing 23 and is adapted to seal and unseal ports 25 formed at diametrically opposite points in the housing within the cylinder 10.

Disposed on the exterior of the cylinder 10 near the open end thereof is a housing 26 within which is telescopically mounted a hollow piston 27. A spring 28 is confined within the piston and bears 20 upon the cylinder 10.

A walking beam 29 is pivoted, as shown at 30, upon an arm 31 formed integral with the plunger valve housing 23. One end of the walking beam is pivotally connected to the piston 27 as shown 25 at 32. The other end of the walking beam is pivotally connected to the plunger valve 24 by means of a link 33 which is pivotally connected at its ends to the walking beam and to the plunger valve as shown at 34 and 35.

A pipe 36 is connected at one end to the T-coupling 20 and at the other end is connected to a short pipe 37 which is integral with the piston housing 26.

The cylinder 10 is provided with a plurality of 35 rows of air intake openings 38 and supply of air to the interior of the cylinder through these openings is controlled by means of a split sleeve 39 which surrounds the exterior of the cylinder between the housings 23 and 26.

In operation, when the motor starts it creates a vacuum in the manifold 22 which is exerted through the pipe 36 upon the piston 27 to move the piston against the tension of its spring 28 and through the instrumentality of the walking beam 29, moves the plunger valve 24 to uncover the ports 25. Now, as the throttle is opened on the carburetor the piston 11 will uncover the openings 38 progressively to permit air to enter and pass through the ports 25 into the manifold 22.

Now, should the motor be suddenly accelerated, as for instance when it is desired to pass another car, the sudden acceleration of the motor reduces the vacuum in the intake manifold and this weak 55

vacuum, being insufficient to overcome the spring 28, the latter instantly moves the piston 27 and through the instrumentality of the walking beam 29 closes the plunger valve 24 to seal the ports 25. 5 Consequently, regardless of the position of the piston 11 in the cylinder 10 no air can pass from the cylinder through the ports 25 into the intake manifold. Thus a richer mixture is available to conform to the requirements of the motor due to 10 sudden acceleration. When the motor picks up its load and starts normally again the vacuum is restored in the intake manifold 22 with resultant removal of the plunger valve 24 to unseal the ports 25 and permit air to again enter the intake 15 manifold.

By swiveling the sleeve 39 on the cylinder 10 one or more rows of the openings 38 may be sealed or uncovered to adapt the device to various conditions of service.

20 From the above description it is thought that the construction and operation of the invention will be fully understood without further explanation.

What is claimed is:

25 1. The combination with a motor intake manifold and throttle rod, of a cylinder operatively connected to the manifold to be exposed to fluctuations of vacuum therein, a piston in the cylinder operatively connected to the throttle rod to be moved as a unit therewith, there being intake 30 openings in the cylinder exposed by the piston when the throttle rod is moved to accelerate the motor, a valve in the cylinder adapted to establish and cut off communication between the cylinder and the manifold, a spring pressed piston on the cylinder operatively connected to the valve

to move as a unit therewith, means exposing the spring pressed piston to fluctuations of vacuum in the manifold, the spring pressed piston being controlled by decreased vacuum in the manifold and closing the valve in the cylinder to prevent air from the cylinder entering the manifold when the motor is suddenly accelerated, and a revolvable sleeve valve on the cylinder having a longitudinal split therein for selectively exposing the openings in the cylinder. 5 10

2. The combination with a motor intake manifold and throttle rod, of a cylinder operatively connected to the manifold to be exposed to fluctuations of vacuum therein, a piston in the cylinder operatively connected to the throttle rod to be moved as a unit therewith, a valve in the cylinder adapted to establish and cut off communication between the cylinder and the manifold, a housing for the valve projecting exteriorly of the cylinder, a housing on the exterior of the cylinder operatively connected to the manifold to be exposed to fluctuations of vacuum therein, a spring pressed piston assembled with the second named housing, a walking beam connecting the spring pressed piston with said valve whereby the valve is moved by the piston to closed position to cut off communication between the cylinder and the manifold during diminished vacuum in the manifold and to establish communication between the manifold and the cylinder when normal vacuum is restored, there being air intake openings in the cylinder controlled by the piston in the cylinder, and a sleeve valve on the cylinder between both housings controlling the openings. 15 20 25 30 35
